UNITED STATES PATENT OFFICE.

GEORGE H. CHAPEL, OF HOWELL, MICHIGAN.

EYEGLASSES.

1,086,439.

Specification of Letters Patent. Patented Feb. 10, 1914.

Application filed June 19, 1913. Serial No. 774,514.

To all whom it may concern:

Be it known that I, GEORGE H. CHAPEL, a citizen of the United States of America, residing at Howell, in the county of Livingston and State of Michigan, have invented certain new and useful Improvements in Eyeglasses, of which the following is a specification, reference being had therein to the accompanying drawings.

- 10 This invention relates to improvements in eye-glass mountings and more particularly to the construction and arrangement of finger pieces of mountings and springs actuating the same.
- 15 The object of the invention is to provide a simple and cheap construction which is such as to greatly facilitate the assembling of parts and to give a strong and rigid bearing for the finger piece, the construction 20 also being such as to provide a ready attachment for the spring and give a very neat and compact arrangement.

To these ends the invention consists in the matters hereinafter set forth and more particularly pointed out in the appended claims reference being had to the accompanying drawing in which—

Figure 1 is an elevation of eye-glasses embodying the invention; Fig. 2 is an edge 30 view of the same; Fig. 3 is an enlarged perspective view of a portion of the mounting; Fig. 4 is an enlarged sectional detail through a portion of the mounting and finger piece and through the spring for actuating the 35 finger piece; Fig. 5 is an enlarged perspective view of a screw post; Fig. 6 is an enlarged detail of a portion of a mounting showing a plan view of Fig. 7 and illustrating a modified construction; and Fig. 7 is 40 a sectional view of the detail shown in Fig. 6 and showing parts in elevation.

As illustrated in the drawings 1, 1 represent lenses which are held in the usual manner by means of clips 2 formed integral with 45 the ends of the bridge 3 in the usual manner. Between the ends of the bowed portion of the bridge and the clips 2, said bridge is broadened and somewhat thickened to form bearing portions 4 each having an opening 50 therein through which a post 5 extends and in which said post is adapted to turn freely. The post has a reduced lower end portion 6 which forms a shoulder 7 intermediate the ends of the post and the portion 6 is adapted 55 to engage the opening in the bridge with its shoulder resting upon the upper surface of the supporting portion 4 of the bridge. The

upper end portion 8 of the post which is of greater diameter than the lower portion 6, is provided with a slightly tapered laterally 60 projecting flange at its upper end forming a slight head 9 on the post which is rounded to provide a smooth upper surface and give a neat appearance. This head is also formed with the usual transverse slot 10 for the engagement of a screw driver and the body 8 is formed with a longitudinal groove 11 in one side extending from one end of the slot 10.

A guard lever 12 of any suitable form and 70 construction is attached to the lower projecting end of the post by screw-threading said end and screwing it into a screwthreaded opening in the lever which is thus held in engagement with the flat lower surface of 75 the bearing portion 4 opposite that surface which is engaged by the shoulder 7 of the post. The guard lever is constructed in the usual manner with a forwardly projecting finger engaging the end and a rearwardly 80 extending portion having a guard 13 formed integral therewith or attached thereto as desired, in an old and well known manner.

A flat volute spring 14 is coiled about the body 8 of the post with one edge resting on 85 the upper surface of the bearing portion 4 of the bridge. The inner end of the spring is inturned and engaged with the slot 11 in the post, and the outer end of the spring is turned outwardly to engage a lug 15 formed 90 or secured to the bridge or adjacent clip member of the mounting. This lug has a laterally extending lip 16 at its end to engage over the end of the spring and hold the spring against its seat upon the bearing 95 portion 4 of the bridge. The flanged upper end or head 9 on the post also assists in holding the spring in place upon its seat.

The spring is so coiled about the post that it tends to turn the post in such a direction 100 that its screwthreaded lower end will be screwed into the finger piece and thus prevent the accidental disengagement of the finger piece from the post. The finger piece may be quickly and easily detached for the 105 purpose of replacement or repair by disengaging the end of the spring from the lug 15, removing the spring, and then turning the post to disengage its screwthreaded end from the finger piece. When the parts are 110 in place, the finger piece has a firm rigid bearing by its engagement with the under side of the bearing or support 4 of the bridge and the post is rigidly supported in its bear-

ing by the engagement of its shoulder with the upper side of the bearing portion. The particular construction and arrangement greatly facilitates the assembling of the 5 parts and gives a very compact construction having a neat appearance. As the spring is attached in such a manner as to constantly hold the screw post against unscrewing, it is unnecessary to rivet or otherwise permanently 10 secure the post to the guard lever. While the guard lever is firmly held against wobbling by the post and the broad bearing which it has against the bridge, the post turns freely in its bearing without binding 15 so that the spring will act upon the lever through the medium of the post to turn the same and hold the guard in gripping position.

In Figs. 6 and 7 a wire spring 17 is shown 20 coiled about the post in place of the volute flat spring 14, one end of the spring 17 being inserted in the slot 10 of the post and the opposite end of the spring engaged with a suitable projection on the bridge or 25 against the adjacent clip. It is obvious that the wire coiled spring operates in the same manner that the flat spring acts and that either form of spring may be used as desired.

Obviously changes may be made in the construction and arrangement of parts without departing from the spirit of my invention and I do not therefore limit myself to the particular form or construction shown.

Having thus fully described my invention what I claim is:

1. In an eye glass mounting the combination of a support, a guard lever at one side of the support, a member having a bearing 40 on the support to turn therein and about which the guard lever is attached, and a spring attached to said member at the opposite side of said support to turn the member and guard lever.

2. In an eye glass mounting, the combination of a support having an opening, a rotatable member within said opening, a guard lever attached to said member at one side of 50 said support, and a spring acting upon said member at the opposite side of the support.

3. In an eye glass mounting the combination of a support having an opening therein, a member rotatable within said opening, a bearing upon one side of the support, a 55 guard lever attached to the rotatable member in contact with the opposite side of said support and a spring attached to and coiled about the rotatable member at the side of the support opposite that engaged by the guard lever to position said lever relatively to said support.

4. In an eye glass mounting, the combination of a support having an opening, a

post rotatable within the opening and having a shoulder to engage one side of the support, a guard lever attached to the post in contact with the opposite side of the support, and a spring to turn the post.

5. In an eye glass mounting, the combination of a support having an opening, a post 70 having a reduced end portion to engage the opening and turn therein, and an end portion having a slot, a guard lever attached to the reduced end of the post in contact with one side of the support, and a coiled 75 spring surrounding the post at the opposite side of the support with one end engaging the slot in the post to turn the same and position the guard lever relatively to the support.

6. In an eye glass mounting the combination with a support having an opening, a post to turn freely within the opening and having a screwthreaded end, a guard lever having a screwthreaded opening engaged by 85 the screwthreaded end of the post, and a spring coiled about the post to turn the post and hold its screwthreaded end engaged with the guard lever.

7. In an eye glass mounting, the combination of a support having an opening, a guard lever engaging one side of the support and provided with a screwthreaded opening, a post having a reduced end to turn within the opening and formed with a shoulder to 95 engage the side of the support opposite that engaged by the guard lever, said post having a screwthreaded end to engage the screwthreaded opening in the guard lever, and a spring coiled about the post and attached 100 thereto to turn the same, said spring resting upon said support at the side thereof opposite that engaged by the guard lever.

8. In an eye glass mounting, the combination of a bridge having a portion forming a support provided with an opening, a guard lever having a screwthreaded opening, a post having a reduced end projecting through the opening in the support and engaging the screwthreaded opening in the guard lever, said post being formed with a shoulder to engage the side of the support opposite that which is engaged by the guard lever and formed with a longitudinal slot in one side, 110 a flat convolute spring surrounding the post with one end engaging the slot in the post, said spring resting upon the support around the post, and a lug on the support to engage the opposite end of the spring.

In testimony whereof I affix my signature 120 in presence of two witnesses.

GEORGE H. CHAPEL.
